TIE FASTENER

Gilbert Cohen, 2383 Montview Drive NW,
Atlanta, Ga. 30305

Filed May 9, 1967, Ser. No. 7,043

Term of patent 7 years

(Cl. D2—424)

FIG. 1 is a front elevational view of a tie fastener showing my new design, the chain, broken away, is continuous as indicated by dash dot lines; and

FIG. 2 is a side elevational view thereof, the side opposite being reversely similar, the chain being broken away for convenience of illustration.

I claim:

The ornamental design for a tie fastener, as shown and described.
